Application May 3, 1933, Serial No. 669,097
Renewed September 3, 1936

20 Claims. (Cl. 197—84)

This invention relates to the printing or impressing of letters or other characters; and more particularly to typewriters, and the like, having mechanisms, or attachments therefor, whereby controlled spacing of the imprinting characters is effected to produce justified lines.

One of the principal objects of the invention is to provide means, in a typewriter, or the like, for effecting spacing of the letters or other characters as they are being printed or impressed in lines so as to produce successive lines justified to a common length.

Another object of the invention is the provision of a device of simple construction effective upon the type characters while being associated into lines to vary the spacing of the characters to produce lines of common length.

Another object of the invention is the provision of a justifying or spacing device having means for coordinating the space length between the impressed characters with the number of characters in a line to produce lines of a predetermined length.

Another object of the invention is the provision in such printing or character impressing mechanism of a spacing device for justifying the lines by reference to a like association of characters in unjustified lines.

It is a further object of the invention to provide a device of the character described, including a laterally movable platen, means to move said platen in step-by-step increments to effect letter spacing, justifying means to differentially vary the length of said step-by-step movements, a copy holder to support unjustified typing, a pointer movable into alignment with the end of an unjustified line, and means actuated as an incident to movement of said pointer to condition said justifying means to differentially control the length of the step-by-step movements of said platen to permit reproduction of an unjustified line to justified length.

A further object of the invention is the provision of a justifying or spacing controlling device which is readily attachable to a typewriter, or other device, for associating or impressing type characters into lines, whereby such devices may operate so that the characters will be associated in successive lines of justified length.

Other objects and advantages of the invention will be apparent from the following description, the accompanying drawings and the appended claims.

For purposes of ready description a preferred embodiment of the invention is disclosed in the

accompanying drawings, as a justifying mechanism for a typewriter.

In the drawings:

Fig. 1 is a side elevational view with parts broken away for clearness of illustration, and shows the spacing device of the invention as a mechanism associated with a typewriting machine;

Fig. 2 is a plan view of the structure shown in Fig. 1;

Fig. 3 is a front elevational view of the character spacing device;

Fig. 4 is a sectional view taken on the line 4—4 of Fig. 3;

Fig. 5 is a vertical sectional view taken on the line 5—5 of Fig. 4;

Fig. 6 is a fragmentary sectional view showing a drive connection and corresponds to the section indicated at 6—6 of Fig. 4;

Fig. 7 is a fragmentary sectional view of the selector mechanism and corresponds to the section indicated at 7—7 of Fig. 4;

Fig. 8 is a fragmentary sectional view taken on the line 8—8 of Fig. 5;

Fig. 9 is a fragmentary view of another form of operating connection between the character spacing device and the device upon which the characters are impressed or associated.

Fig. 10 is a fragmentary view showing lines of characters associated in unjustified lines; and

Fig. 11 is a view similar to Fig. 10 and shows the characters associated in justified lines.

When associating type characters as words or other character groups into lines the lines would normally be of varying length due to the varying number of letters in the several words which can be included within a line of a predetermined maximum length. In a typewriter, for example, the characters are associated in the typed lines providing character spaces of uniform length, and because the character groups can only be separated at established places such, for example, as at the end of a word or at the end of a syllable where a hyphen may be used, the lines necessarily vary in length. In such association of characters as heretofore impressed only one margin might be aligned. This invention provides for the association of such characters in justified lines,—that is to say, in lines having a common length so that both margins are aligned. This is accomplished by varying the length of the character spaces in accordance with the number of characters in the line. The length of space is varied with respect to what might be termed a normal space length. The adjusted space length for any line is established by reference to

a like association of the same characters arranged at normal character spacing and by proportioning the character spacing of the justified line in accordance with the length of the unjustified line.

5 The justifier provides the operating connection between that part of a type character associating device from which the type characters are associated, and that part which is relatively movable thereto and upon which the type characters are adapted to be associated. By controlling the relative movement of these parts which, for purposes of description, have been termed the frame and platen respectively, the characters may be 10 readily associated in lines of common length.

15 The type character spacing device or justifier is readily applicable to different uses, for example, as for spacing type characters that are associated by imprinting as in typewriting, or by controlling the spacing of the associated characters into justified form for the production of a stencil or the like. The spacing device or justifier may be constructed as an integral part of a type character associating device or may be constructed as an attachment therefor as is shown in the illustrated embodiment of the invention wherein the justifier is applied as an attachment for a typewriter so that typewritten lines may be produced to a justified or common length.

20 In the drawings, in which like characters of reference designate like parts throughout the several views thereof, the numeral 10 designates the type character spacing device or justifier which is shown as having a frame portion 11 and a carriage 12 which is movable thereon. The justifier as herein shown is mounted upon a common base 13 with a typewriter 14 although it is to be understood that the justifier need not be a separate part from the typewriter or other 25 character associating device. The typewriter comprises generally a frame 15 and a carriage 16 that is movable thereon. The justifier is operatively connected to the typewriter for controlling the movement of the typewriter carriage 16 whereby the type characters associated or imprinted in word or other sequence relationship on the platen 17 of the typewriter carriage 16 may be spaced to produce lines of common length, that is to say, so that the lines may be justified.

30 The justifier is readily applicable to different makes of typewriters and for purposes of illustration has been shown as associated with a "Royal" typewriter. As the operation and mechanism of this construction of typewriter are well known, being such as described in the patent to Hess et al. 1,427,464, August 29, 1922, only so much of the mechanism of this typewriter is illustrated in detail as is needed in order to permit of a clear understanding of the operation of the typewriter and attached justifier.

35 As mentioned above, the justifier serves to control the length of character space movement of the typewriter platen 17 which is operatively connected to the carriage 12. This is accomplished by the provision of mechanism between the relatively movable justifier parts 11 and 12 so that the space length of a character movement may be varied in accordance with the number of characters that are to be associated in a justified line. For any given justified line the character spaces are of uniform length, and in the different lines constituting a sheet of copy the space length for a line varies in accordance with the number of character spaces therein.

40 75 The variation in the space length is obtained

through provision of a selective drive operable between the frame 11 and carriage 12 and which may be readily controlled as to the extent of a space movement, and includes a selector whereby a proper space length relationship may be established to produce lines to a common length.

45 In the form of type character spacing device illustrated the carriage 12 is supported for movement upon the frame 11. As shown, one side of the frame 11 is provided with a guideway 20 having a groove 21 that is cooperatively related to a similar groove in the guideway 22 on the carriage 12. A plurality of bearing balls 23 are positioned between the guideway grooves and provide a free moving support at one side of the carriage 12. Additional support is afforded by a rod 25 that is shown mounted between laterally extending brackets 26 on the frame 11. This rod is slidably engaged by a bracket 27 which is attached to and extends downwardly from the carriage 12. Carriage movement in the right hand direction is limited by provision of a sleeve 28 on the rod 25 which serves as a stop between the frame bracket 26 and the carriage bracket 27. This stop mechanism also serves in locating the left hand margin position of the typewriter carriage 16.

50 The carriage 12 is constantly urged toward the left (as viewed in Figs. 2, 3 and 4) and is controlled in its movement in that direction by an escapement mechanism. Carriage movement to the left is by means of a spring and ribbon such as is common and well known for the movement of a typewriter carriage. As shown, a stud 30 (Fig. 5) on the frame 11 carries a rotatable spool 31 upon which a ribbon 32 is wrapped. One end 55 of the ribbon is fixed to the spool and the other end is connected at 33 to the carriage. A suitable spring is attached to the stud 30 and spool 31 to tension the spool for movement of the carriage to the left.

55 The escapement which controls the space by space movement of the carriage 12, and which is shown at 35, (Figs. 5 and 8) may be of any suitable type such, for example, as that illustrated which is well known for controlling the movement of a typewriter carriage. As shown, the escapement is mounted upon a bracket 36 which is attached to the frame 11 and comprises a rocking member 37 pivotally mounted upon the frame 36 by means of pivot members 38. The 60 frame 36 also carries rotatable star wheel or escapement wheel 40 that is operatively connected to the carriage 12 and has angularly spaced teeth 41 which are engaged in succession by parts carried on the rocking frame 37 for spacing movement of the carriage. A pivotally movable arm 42 on the rocking member is spring tensioned for movement between a fixed stop 43 and an adjustable stop 44. In one position of the rocking member the arm 42 stands in the 65 path of movement of the escapement wheel teeth and, as a result of the spring tension on the carriage 12, is held by the tooth against the adjustable stop 44. Upon pivotally moving the rocking member, as by depressing a key on the typewriter, the upper end of the member 37 swings forwardly an amount sufficient to disengage the arm 42 and engage a finger 46 with the tooth previously held by the arm 42. This permits the arm to move under urge of its spring 70 47 so that upon return movement of the frame 37 the arm will engage the next tooth and thus permit a movement of the wheel 40 by the amount of one tooth space. The escapement wheel 40 has rotatably mounted upon it a pinion 75

48 which is caused to move with the escapement wheel in one direction of its movement through provision of a spring pressed pawl 49. This pawl serves as a drive connection between the pinion and wheel in the direction of feeding movement of the carriage and serves also, by overrunning, to permit independent return movement of the carriage.

The selective drive connection from the pinion 48 to the carriage 12 is through a gear 50 which is interconnected with other gears of different sizes for rotation with a common shaft 59 carried by the frame 44. The several gears rotate together and mesh with racks that may be selectively connected to the carriage 12. The gears are proportioned so that the pitch diameter of each differs from the pitch diameter of an adjacent gear by an amount sufficient to change the number of character spaces in a predetermined line length by one whole character space. For example, gear 50 may be constructed to have a pitch diameter such that the escapement mechanism will provide for sixty-five character spaces in a line six and one-half inches long. The next adjacent gear 51 is sufficiently larger that only sixty-four character space movements by the escapement are necessary to move the carriage the same amount that it is moved by gear 50 in sixty-five character spaces, that is, to provide the same length line. This same relationship exists between the gears 52 and 51 and so on between gears 53, 54, 55, to gear 56 which is of such size that fifty-nine character spaces will be distributed uniformly in the six and one-half inch line. The corresponding racks, which are indicated by the numerals 60 to 66, (Figs. 4 and 5) are all of like form and are slidably mounted upon the carriage. As shown, the carriage is provided with spaced blocks 67 and 68. These blocks are notched on their underside to receive the racks as indicated at 69 and position the racks in alignment with the corresponding gears. Each rack is slotted as indicated at 57 corresponding to the spacing of the blocks, and each is held for sliding movement within the blocks through provision of pins 58 that pass through the rack slots 57 (Fig. 7).

The racks are selectively engaged with the carriage 12 through provision of a latching mechanism which is duplicated for each rack. As shown, freely movable arms 70 to 76 (Figs. 4 and 7) are positioned adjacent the racks for rocking movement upon the right hand pin 58. Each arm is provided with a notch 77 which is adapted to engage a pin projection 78 on the associated rack. The arms are of like shape and consequently the notches 77 all stand an equal distance from the pivot pin 58 upon which the arms are mounted. The arms are urged downwardly by similar springs 79. The associated gears and racks are assembled in such relationship that when the carriage is moved to the right hand position the pins 78 will stand axially aligned and beneath the arm notches 77 for engagement thereby.

It should be understood that any desired line length may be justified by a proper selection of drive gears corresponding to the gears 50 to 56. However, the gears must be of related sizes so that for a given line length the gears will permit carriage movement of an amount differing in adjacently related gears by one whole character space length. The gears are preferably selected as to size so that the gear which provides the greatest number of character spaces for a given

line length will produce space lengths which are normal for the size of characters used. For example, when the justifier is used with a typewriter the spacing afforded by the gear mentioned is the same as the spacing produced by the typewriter escapement. For convenience in description this has been called normal spacing.

It will be obvious that other sizes of gears may be used so long as their relationship is such that they differ one from another in amounts to produce a one character space difference in the predetermined line length. It will also be apparent that any one of the gears may be utilized to provide the desired normal space length, so obviously the random length lines of unjustified copy can be condensed as well as elongated.

A selector is provided whereby the proper arm may be moved into engaging position for operatively connecting the desired rack and gear to the carriage. The selector comprises a rotatable shaft 87 which is carried in bearings 88 on the carriage 12. The shaft has mounted upon it a plurality of axially spaced cams indicated by the numerals 80 to 86 (Fig. 4) and positioned corresponding to the arms. Each arm has at its outward end a roller 89 which engages the periphery of its associated cam. As shown, the cams are formed generally circular and each has an indentation 90 of sufficient depth to permit arm movement whereby a notch 77 may engage its associated pin 78. The cams are fixed to the shaft 87 so that the cam notches are equally spaced in angular relationship, and so that only one arm may move to engaging position at a time. The selecting movement of the cam shaft is through provision of a readily accessible knob 91.

Indicating means are associated with the selector whereby the positioning of the selector may be readily observed, and to aid in effecting driving engagement with the proper gear and rack assembly. As shown, the shaft 87 has fixed to it a cam 93 which is constructed with a series of stepped faces corresponding in number to the cams 80 to 86 and of progressively increasing distance from the shaft axis. A bar 94 that is slidably carried by the blocks 67 and 68 operatively engages the cam 93 for movement thereby in accordance with the positioning of the shaft 87 and its associated parts. The bar 94 is slidably mounted upon the blocks 67 and 68 through provision of slots 95 that are engaged by screws 96 held in the blocks. The end of the bar adjacent the cam 93 is provided with a roller 97 which is urged into contacting engagement with the cam 93 by a spring 98. The bar 94 carries a pointer 99 that moves in accordance with the cam positioning and thus serves as an indicator for readily adjusting the selector. The radial spacing of the cam faces is such that the pointer is moved by adjacently related faces an amount equal to a normal character space. The cam 93 is fixed to the shaft 87 so that the cam face of shortest radius will engage the roller of the pointer bar 94 when the cam 80 is positioned to permit engagement of the arm 70 with the rack 60 so that the gear 50 is connected to the carriage 12. As the shaft is rotated to bring other of the cams 80 to 86 into arm engaging position the pointer moves accordingly.

As mentioned above, the justifier carriage 12 has a driving connection with the typewriter carriage 16 to control the movement of the platen 17. The justifier is also connected to the typewriter so that character space movements are im-

parted to the justifier carriage in accordance with typewriter operation, that is, the justifier carriage is moved as the typewriter keys are depressed. This operation is produced by connecting the justifier escapement with the typewriter escapement, and by rendering inoperative the connection between the typewriter escapement and the typewriter carriage 16 so that the movement of the carriage 16 is controlled by the movement of the justifier carriage 12. As shown particularly in Figs. 3 and 5, the rocking member 31 of the justifier escapement carries a roller 101 that is engaged by an arm 102 on a rock shaft 103 which carries also a second arm 104. The arm 104 has a link connection 105 with the bar 107 of the typewriter escapement mechanism. The bar 107 is supported for rocking movement and moves to actuate the typewriter escapement upon depression of any key. The rocking movement of the bar 107 is transmitted to the justifier escapement through the linkage just described so that the justifier escapement is actuated in accordance with the operation of the typewriter escapement. As mentioned above, the operating connection between the typewriter escapement and the typewriter carriage is rendered inoperative. This is accomplished by holding the carriage escapement release lever 110 in depressed position through provision of a suitable latch 111. Upon depressing the lever 110 the escapement rack 112 is moved out of engagement with the pinion 113 that is associated with the typewriter escapement wheel 114.

Any suitable driving connection may be provided whereby the typewriter carriage 16 and platen 17 will move in accordance with the movement of the justifier carriage 12. As shown, there is attached to the bracket 27 of the carriage 12 a projecting finger 116 which extends forwardly at the elevation of the typewriter tabular bar 117. This finger is operatively connected to the carriage 16 by the insertion in the bar 117 of readily removable clips 118 at each side of the finger 116. Independent movement of the typewriter carriage is obtained by releasing the latch 111 to render the typewriter escapement operative, and by disengaging the clips 118 so that the carriages are disconnected from one another.

To produce associated type characters in lines of justified length the characters are first associated in lines of random length by using normal spacing. This copy is then used as an index or guide for reproducing the characters in lines of justified length. To use the illustrated structure to provide an example of this, the matter to be reproduced in justified lines is first typed on the typewriter in the normal manner to produce a sheet of copy corresponding to that shown in Fig. 10. The unjustified copy is produced within the limits of a predetermined line length as indicated by the vertical guide lines 120 and 120'. These lines are spaced apart according to the predetermined line length at which justification is obtained, that is at which the coordinated gear and rack combinations of the justifier varying by whole space length differences will produce typed lines of the same length. In the illustrated example we have assumed sixty-five character spaces of normal length to be divided into a six and one-half inch line. The other space lengths also divide evenly into a six and one-half inch line. The guide lines 120 and 120' are therefore spaced apart six and one-half inches. In making the original copy on the typewriter the typed lines must all terminate within

the limits established by the guide lines. This is readily accomplished by either terminating the typed line at the end of a word, or by terminating the line where a word may be hyphenated as indicated.

In the illustrated construction provision has been made to justify as much as six space lengths in the predetermined line length. This means, including the normal space length afforded by gear 50, that lines varying as much as seven spaces can be justified. It has been found by practice that practically any line may be terminated within a seven space variation either by ending a word or by hyphenating. In those few instances where a greater variation exists justification is obtained by inserting an additional character space between a sufficient number of adjacently related words that the line is reproduced to justified length.

In order that the unjustified copy may be readily used as a guide in adjusting the justifier to produce justified lines a carrier is provided for such copy. As shown, the justifier carriage has a copy carrier 115 mounted above it upon brackets 116. The copy carrier 115 comprises a frame 117 upon which a roller 118 is rotatably mounted. The roller 118 is arranged to support the unjustified copy so that it may be readily moved to a desired position by turning the roller knob 119. Suitable adjustable clips 121 also aid in positioning the copy in the frame 117. The unjustified copy is thus held so that it can be easily read by the operator when reproducing it in justified form, and so that the pointer of the selector may be readily moved with respect to the unjustified line lengths for adjustment of the character space length. As shown, the pointer 99 is of sufficient length that its end 122 terminates adjacent the front face of the roller. The pointer is guided by provision of an overlying bar 123 which permits free sliding movement of the pointer.

The device is prepared to produce justified lines by moving the carriage to the right hand position and by turning the selector knob 91 so that the pointer stands in the position of the predetermined line length. This corresponds to the cam positioning in which gear 50 and rack 60 are cooperatively connected to the carriage 12. The unjustified copy is then placed in the carrier 115 so that the right hand margin of the predetermined line length stands in registration with the pointer. This is readily accomplished by providing the unjustified copy with guide lines or by placing a reference mark on the copy in the position of the right hand margin. Having placed the copy in the carrier as described the selector knob 91 is then turned to move the pointer 99 into registration with the last letter of the line that is to be recopied in justified form. This selects the proper gear and rack that will produce character spacing of the justifier such that the number of characters in the selected line will be adjusted to produce a like number of character spaces to justified length.

As shown in the unjustified copy illustrated in Fig. 10, the first line is two characters short of predetermined line length. After placing the copy in the carrier with the first line in view the knob 91 is turned an amount sufficient to bring the pointer 99 into registration with the last letter of the line, which brings the cam 82 into position for engagement of the arm 72 with its rack 62 so that gear 52 will connect the justifier escapement to the carriage. The copy is then re-

produced on the typewriter and, by having selected a proper length of character space, will be reproduced to justified line length as is shown in the first line of the copy illustrated in Fig. 11. 5 This same procedure is followed for each succeeding line of the original unjustified copy, and in each line the selection is made in accordance with the unjustified line length.

In order to insure maintenance of the selected 10 character space length throughout the extent of any given line, whereby all of the character spaces of that line are of uniform extent, a locking device is provided so that selection can only be made at one position in the carriage travel. In 15 the illustrated embodiment of the invention this selection is made at the right hand limit of carriage movement in which position the lock is disengaged. Also, in this position, the latch pins 78 are aligned.

20 As shown in Fig. 3, a lever arm 128 is pivotally attached at 129 to the carriage 12 and is urged in a counterclockwise direction by provision of a spring 130. The arm has a detent finger 131 which is adapted to engage a notched wheel 132 that is fixed to the shaft 87 and is provided with notches 133 corresponding in positioning to the indented portions 90 of the cams 80 to 86. The movement of the lever arm 128 is controlled by a horizontally extending bar 134 which extends 25 along the front of the frame 11 and is positioned so that the lower end 135 of the arm 128 can override the bar 134 only when the detent 131 is in engagement with a notch of the wheel, 132. The parts 128 and 134 are coordinated as to positioning so that when the carriage is in the extreme right hand position the arm end 135 may drop down an amount sufficient to release the detent 131. In this position the arm end 135 operates against the end of the bar 134 as a positive 30 stop whereby the carriage may not be moved until the arm 128 is rocked by depressing the handle portion 136 to engage the detent 131 and release the arm end 135. Upon making the proper gear selection the handle portion 136 is depressed 35 whereupon the carriage moves to the left an amount just sufficient to cause the arm end 135 to override the bar 134. The selected line is then typed in justified form and the carriage is returned for selection of character space length for 40 the next succeeding line.

50 As mentioned above, the justifier drive connection incorporating the gear 50 and rack 60 preferably provides a normal character space length, that is, a space length corresponding to the normal character spacing of the typewriter. The original unjustified copy may therefore be typed on the platen of the typewriter carriage 16 either by using the typewriter escapement or the justifier escapement as desired.

60 The justifier may be arranged to justify any desired line length by a proper selection of gears constituting the drive connection. That is, having determined the justified line length, gears are selected for assembly on the common shaft having a pitch diameter relationship such that the character space length will divide evenly into the justified line length, and so that the number of character spaces afforded by any given gear in traversing the carriage the distance of the justified line length will differ from the number of spaces produced by adjacently positioned gears by one whole character space length. This is clearly brought out in the description of the illustrated embodiment of the invention wherein 65 the justified line is assumed to be six and one-

half inches long, and the normal spacing is taken to be ten characters per inch, or sixty-five character spaces of normal length in the justified line. The gears are proportioned so that sixty-five or less whole character spaces are produced, and the variation between adjacent gears is by steps of one whole character space length in the justified line length. As a further illustration, a justified line length of seven inches is assumed for a device having a normal character 10 spacing of twelve characters per inch or eighty-four character spaces for the justified line. In this instance the gears will be proportioned so that carriage travel for the justified line length will be eighty-four or less whole spaces, differing 15 in adjacent gears by one whole space. If an assembly of seven gears is provided the range of justification will then be from eighty-four to seventy-eight spaces. If desired, the number of gears, together with the associated rack and 20 other selecting mechanism, may be increased in number to provide a greater range of justification. It has been found, however, that a seven space range is adequate.

25 When the justifier is to be used as an attachment on devices which will not permit a compact mounting such as is illustrated in those figures of the drawings showing the justifier as a closely positioned typewriter attachment the justifier may be mounted in any desired position remote 30 from the device upon which type characters are associated by provision of an operating connection such as is shown in Fig. 9 wherein the carriage of the justifier and the carriage upon which the type characters are associated are interconnected 35 by means of a shaft. As shown, the justifier carriage 12' has attached to it a rack 140 which extends parallel to the direction of travel of the carriage. A gear 141 which is fixed to a shaft 142 meshes with the rack 140. The 40 shaft 142 is supported in suitable brackets on the justifier frame and on a fixed portion of the device upon which the type characters are associated. The shaft end adjacent the typewriter, or whatever device is to be controlled 45 by the justifier, carries a gear 143 that is in meshing engagement with a rack 144 that is mounted upon a carriage portion 145 of the type character associating device. The shaft 142 may be of any desired length, and the operating linkage which operates the justifier escapement is proportioned accordingly. Also the justifying mechanism may be built right into the typewriter in place of the regular escapement. And, of course, the same mechanism is effective for 50 producing such predetermined spacing in successive lines of type characters of varying sequence and arrangement as will give a predetermined length for successive or succeeding lines. 55 And, obviously, when desired the variable spacing mechanism may be made applicable to devices other than the typewriter in which the type or impressing characters are effective within a given zone or space and the material being acted upon is moved with relation thereto.

60 While the method herein described, and the form of apparatus for carrying this method into effect, constitute preferred embodiments of the invention, it is to be understood that the invention is not limited to this precise method and form of apparatus, and that changes may be made in either without departing from the scope 70 of the invention which is defined in the appended claims.

What is claimed is:

1. A type character spacing device of the character described adapted for associating type characters in lines having aligned margins, said device comprising parts including a frame and platen relatively movable for character spacing, selectively variable spacing means connecting said parts and adapted upon actuation to release said parts for a character space movement, control means adjustable to selectively vary the spacing means to alter the length of the character space movement, and locking means to hold the control means in adjusted position except in a predetermined position of said platen.
- 15 2. A type character spacing device of the character described adapted for associating type characters in lines having aligned margins, said device comprising a relatively movable frame and platen, spacing means connecting said parts and adapted upon actuation to release said parts for a character space movement, means for selectively varying the length of the character space movement between said parts, locking means engageable with said space varying means to hold 25 said means in selected position, and means for maintaining said locking means engaged except in one margin position.
- 30 3. A type character spacing device of the character described adapted for associating type characters in lines having aligned margins, said device comprising a frame and a platen movable thereon, spacing means for moving said platen by character space movements, a plurality of connecting members of fixed and different space 35 length characteristics adapted for selective attachment between said spacing means and platen, adjustable means for selectively attaching a connecting member for imparting to the platen a character space movement of desired length, 40 locking means normally tending to prevent actuation of said adjustable means.
- 45 4. In a type character spacing device of the character described adapted to associate type characters in justified lines from copy constituting like associations of characters in unjustified lines, a carriage, a platen operatively connected thereto upon which type characters are adapted to be associated in justified lines, a holder for holding the unjustified copy, means 50 for moving the carriage, means for controlling character space movement of the carriage, said controlling means comprising a plurality of drive connections for imparting character space movement of different lengths, indicating means extending toward the copy holder for registration with a line end of the copy and movable into registration with a selected line end, and means 55 operated with the indicating means for selectively engaging a drive connection to impart carriage movement of a character space length coordinated with the length of a line of unjustified copy to reproduce the characters of that line in justified length on the platen.
- 65 5. In a type character spacing device of the character described adapted to associate type characters in justified lines from copy constituting like associations of characters in unjustified lines, a carriage, a platen attached thereto upon which type characters are adapted to be 70 associated in justified lines, means for supporting the unjustified copy on said carriage, means for moving said carriage, means for adjustably controlling the character space length movement of the carriage, a pointer directed toward the 75 unjustified copy and adapted to assume a post-

tion corresponding to a predetermined line length, means for moving the pointer from the first mentioned position into registration with the end of a line of unjustified copy and for simultaneously adjusting the length of carriage character space movement whereby the characters associated on the platen are justified to the predetermined line length. 5

6. In a type character spacing device of the character described comprising a frame and a carriage movable thereon, a platen carried by said carriage, means for moving the carriage by character spaces and for selectively varying the length of the character spaces comprising a plurality of members freely movable on said carriage, a latch on said carriage for each member, said latches being movable into engagement with the corresponding members to afford a driving engagement between a member and the carriage, a rotatable shaft, angularly related cams 20 on said shaft axially spaced in positions corresponding to the positioning of said latches and adapted upon shaft rotation to successively move each latch into engagement with its member. 15

7. In a type character spacing device of the character described comprising a frame and a carriage movable thereon, a platen carried by said carriage, means for moving the carriage by character spaces and for selectively varying the length of the character spaces comprising a plurality of members freely movable on said carriage, a latch on said carriage for each member, said latches being movable into engagement with the corresponding members to afford a driving engagement between a member and the carriage, 35 a rotatable shaft, angularly related cams on said shaft axially spaced in positions corresponding to the positioning of said latches and adapted upon shaft actuation to successively move each latch into engagement with its member, and 40 means for indicating the latch positioning comprising a cam member on said shaft and a pointer in operating engagement with said cam. 25

8. A justifying attachment for a typewriter comprising a frame portion adapted to be fixedly mounted with respect to the typewriter frame, a justifier carriage movably mounted on said justifier frame portion and adapted to traverse a predetermined line length, means for operatively connecting the justifier carriage and the carriage of the typewriter, a platen on said typewriter carriage, an escapement mechanism for the justifier carriage, means for operatively connecting the justifier escapement and the escapement mechanism of the typewriter, means 55 for rendering the typewriter escapement mechanism inoperative, means for holding copy written in unjustified lines, a plurality of justifier carriage feeding means each affording a different length of character space, indicating means extending toward the copy holder for registration with a line end of the copy and movable into registration with a selected line end, and means 60 operated with the indicating means for selectively engaging a carriage feeding means affording a length of character spacing such as to reproduce the characters forming a line of unjustified copy into a line of predetermined length on the platen. 65

9. In a type character spacing device of the character described comprising a platen supporting carriage movable between fixed margin limits, an escapement mechanism adapted upon actuation to release said carriage for a character space movement, a plurality of relatively fixed 70 75

- gears of differing pitch diameter operatively connected to said escapement to provide space movements of varying extent, a rack for each of said gears, latch receiving means on each rack, aligned 5 latching means on the carriage selectively engageable with said rack latch receiving means, the gear and rack relationship being such that the latch receiving means are aligned in one margin position of the platen.
10. In a type character spacing device of the character described comprising a platen supporting carriage movable between fixed margin positions, an escapement mechanism adapted upon actuation to release said carriage for a 15 character space movement, a plurality of relatively fixed gears of differing pitch diameter in constant operative engagement with said escapement, a rack in meshing engagement with each gear, latch receiving means on each of said racks, 20 a latch on the carriage for each of said rack latch receiving means, and a rotatable control member for the latches to selectively and individually engage a rack to the carriage.
11. In a device for reproducing lines of type 25 characters arranged as unjustified copy in lines of random length to lines of predetermined common length, adjustable spacing means, a copy holder to hold the unjustified copy in predetermined position, and means registerable with a 30 random length line of the copy in the copy holder as an index in adjusting the character spacing for reproduction of that line to predetermined length.
12. In a device for associating type characters 35 in justified lines from like associations of characters in unjustified lines, a carrier for unjustified copy, adjustably variable spacing means, and means extending toward the copy carrier and movable into registration with an unjustified line 40 end to adjust the spacing means by an amount to space the characters of that line to justified line length.
13. In a type character spacing device of the character described comprising a platen movable 45 between fixed margin limits, an escapement mechanism adapted upon actuation to release said platen for a character space movement, variable spacing means operable to vary the length of character space with respect to a character 50 space of normal length, a rotatable control member for the spacing means, and means for indicating the positioning of the control member comprising a stepped cam on the control member and a pointer operated by said cam, said 55 cam steps being graduated to move the pointer in amounts of one normal character space length.
14. In a type character spacing device of the character described comprising a platen supporting carriage movable between fixed margin limits, 60 an escapement mechanism adapted upon actuation to release said carriage for a character space movement, a plurality of relatively fixed gears of differing pitch diameter operatively connected to said escapement, a rack for each gear, 65 latch receiving means on each of said racks, a latch on the carriage for each of said rack latch receiving means, a rotatable control member for the latches, means thereon for selectively engaging the racks at angularly spaced points 70 on the control member, and means for indicating the positioning of the control member comprising a cam on the control member and a pointer operated by said cam, said cam having stepped faces coordinated as to positioning with the latching positions.
15. A device for associating type characters in justified lines comprising a movable platen, a carrier for copy arranged in lines of uniform character spacing and random length within the limits of the justified line length, means for moving the platen by character spaces, adjusting means for varying the extent of a space movement, and indicating means operable with the adjusting means and extending toward the copy carrier for registration with a random line end 10 as an index of the adjusted position of the spacing means for reproduction of the indicated line to justified length.
16. In a type character spacing device for justifying random length lines into lines of predetermined length having aligned margins, the combination of a platen movable between predetermined margin limits, an escapement mechanism adapted upon actuation to release said platen for a character space movement, adjustable spacing means comprising a plurality of adjacently related gears of differing pitch diameter, each gear having an intermeshing rack, the pitch relationship of the adjacent gears being such as to traverse the platen between the said 25 margin limits by a difference of one whole character space, means for selectively attaching a desired gear and rack combination between the escapement and the platen, and locking means to defeat operation of said last mentioned means 30 when the platen is intermediate its marginal positions.
17. In a type character spacing device of the character described, the combination of a platen movable between predetermined marginal positions, 35 an escapement mechanism, a member movable under control of said escapement, said escapement mechanism being adapted upon actuation to release said member for a character space movement, adjustable spacing means between the platen and member to transmit motion to the platen and to vary the platen travel with respect to the escapement movement, a rotatable control movable to predetermined positions for adjustment of the spacing means to provide space variation of one whole character space 40 in the platen travel between the margin limits, and locking means to defeat operation of said rotatable control when said platen is intermediate its marginal positions.
18. A justifying device attachable as a unit to a typewriter having a frame, movable platen, a platen carriage, and movable key bars, said device controlling the spacing of the typewriter platen and comprising a supporting frame adapted to be fixed to the typewriter frame, a platen controlling carriage member supported by said supporting frame for rectilinear movement, means for selectively attaching the platen carriage member to the typewriter platen carriage 50 at a desired one of a plurality of positions spaced in the direction of movement of the platen carriage member, escapement means supported by said supporting frame, means operated by the keys of the typewriter for operating said escapement, and variable spacing means between the escapement means and the platen controlling member adjustable to positions affording predetermined space movements of the typewriter platen which are aliquot fractional parts of a 55 predetermined line length, and means for adjusting the variable spacing means.
19. A justifying device for reproducing lines of type characters arranged as unjustified copy in lines of random length to lines of predetermined 60

- common length, comprising a platen, adjustable spacing means for the platen, a copy carrier affording a predetermined copy position on the justifier for unjustified copy that is to be reproduced into justified form, control means for the adjustable spacing means, and means operable with the control means and movable to a desired one of a plurality of positions each having a predetermined relationship to the copy position on the copy carrier to establish a positioning for the adjustable spacing means coordinated to the length of the line of copy to be reproduced.
20. A justifying device for reproducing lines of type characters arranged as unjustified copy in lines of random lengths to lines of predetermined length comprising a type platen, movable key bars adapted for cooperation with said

platens, a platen carriage, means supporting said carriage for rectilinear movement, a justifier carriage mounted for movement in a path parallel to the path of movement of the platen carriage, means for selectively attaching the platen carriage to the justifier carriage at a desired one of a plurality of positions spaced in the direction of platen movement for location of the left hand margin position of justified lines, escapement means operated by said key bars, and adjustable spacing means between the escapement means and the justifier carriage adjustable to positions affording predetermined space movements of the justifier carriage which are aliquot fractional parts of a predetermined line length. 5 10 15
